UNITED STATES PATENT OFFICE.

LEE P. HYNES, OF ALBANY, NEW YORK, ASSIGNOR TO CONSOLIDATED CAR-HEATING COMPANY, OF ALBANY, NEW YORK, A CORPORATION OF WEST VIRGINIA.

DOOR CONTROL.

Application filed April 16, 1920. Serial No. 374,321.

To all whom it may concern:

Be it known that I, LEE P. HYNES, a citizen of the United States, residing at Albany, in the county of Albany and State of New York, have invented certain new and useful Improvements in Door Controls, the following being a full, clear, and exact disclosure of the one form of my invention which I at present deem preferable.

For a detailed description of the present form of my invention, reference may be had to the following specification and to the accompanying drawings forming a part thereof, wherein—

Fig. 1 shows my device diagrammatically and

Fig. 2 shows a modification.

My invention relates to the controlling means for a power-operated door, whereby it may be opened and closed by the doorman upon pressing the appropriate push buttons, and also be automatically reversed and opened by the door shoe in the event of obstruction and then, after being more or less fully opened, is again reversed and closed automatically, provided the obstruction is not encountered a second time.

Referring to the drawing, A designates a door designed to operate by a motor of any suitable or desired construction. For example, a pneumatic motor may be employed, the same being controlled by a magnetic valve-shifting device, the magnets of which are diagrammatically illustrated at C' and O'; the former controlling the door closing valve and the latter the door opening valve. Motors of this type are well-known in the art, and are typically illustrated in Letters Patent 1,247,653 to Farmer and 1,287,717 to McElroy, and the invention for purposes of illustration, is assumed to be associated with such a motor, although it is not limited in this particular. In view of the well-known construction and operation of motors of this character detailed illustration thereof is considered unnecessary. Door A is also provided on its front edge with a yielding shoe or fender B such as is familiar to those skilled in the art.

The opening and closing push buttons for the doorman are shown at O and C. In this case the buttons are each arranged to close and hold closed its respective circuit until the other button is pushed. Thus the two buttons are on opposite ends of a slide K to

which are pivoted two spring-connected contact levers, which, in the position shown in the drawing, contact with and electrically connect the points 6 and 7, having been thrown into this position by pushing in button C. When the button O is next pushed in the spring will act, at the dead-center point, to snap the levers away from points 6 and 7 into contact with points 4 and 5 which will then be electrically connected. At the same time button C will be thrown out as button O is forced in ready for the next operation.

When the door meets an obstruction the shoe B will be forced in towards the door and close switch D so long as it remains in that relation to the door. As the door travels the electrical connection with switch D will be maintained by the parallel metallic rods F and G upon which slide the contacts S and W attached to and moving with the door. As the door approaches its closed position, shown in the drawing, contact W moves off from rod G and contact S moves onto a short rod E. In the open position of the door, or at any desired approximation to that position, contact W runs off rod G and contact S runs off rod F and respectively engage two short rods T and R. Thus it is only when the door is closed and contact S is bridging rods E and F that the push button O, by connecting points 4 and 5, can establish a circuit through opening magnet O¹ from battery H, that circuit being from battery H, to contacts 4 and 5, thence through rods E and F, to magnet O¹ and ground. At that time also the shoe B has no control of the door, since even if the shoe is pressed in to close switch D, the contact W does not touch rod G to which the battery is connected. Moreover, it is only when the door is in its open position, with contact S bridging rods T and R, that the push button C can close a circuit to the door-closing magnet C¹—i. e., from battery H to points 6 and 7, rods T, R and magnet C¹. But in intermediate positions, with contacts S and W on rods F and G, any movement of shoe B with respect to the door—for instance, when shoe B encounters an obstruction and closes switch D—a circuit will be closed from battery H, to rod G, contact W, switch D, contact S, rod F, and door-opening magnet O¹ to ground. Thereupon the door, which has been moving towards closed position will

be instantly reversed and proceed to open until contact W leaves rod G and contact S bridges rods T and R. It will be observed that the door in its closing movement breaks the circuit to magnet C' when contact S moves out of engagement with the contacts T and R. In control mechanism such as disclosed in the patents above identified, closing of the circuit through magnet C' will operate the valve shifter to introduce power into the engine. When the circuit to the coil is broken by closing of the door to the valve shifter, as is well-known in the art, is not disturbed and the engine continues to operate. If however, the circuit to coil O' is closed by the contact D, the position of the valve shifter is immediately reversed, thereby shutting off power to the door closing side of the engine and introducing power to the door opening side, the effect of which is to instantly reverse the door movement. This movement continues until the door reaches the limit of its opening movement or at least until the magnet coil C' is again energized. Thereupon, since points 6 and 7 have been left connected by the previous action of door-closing button C, a circuit will be established from battery H, as heretofore described, through door-closing magnet C' and the door will be again reversed automatically and make its complete closing run, unless it should once more encounter the obstruction, when the aforesaid action will be repeated. In this way the door will move back and forth automatically so long as the obstruction is present. Its reciprocation can be stopped at any time by pushing button O which will disconnect points 6 and 7, the door, if in the act of closing, will finish its closing run, then automatically move to open position, make its opening run and stop, or, if in the act of opening, will finish its opening run and stop. In ordinary operation the door, when standing open will bridge rods T and R, having been brought to that open position by pushing button O which has left the door-closing circuit broken at points 6 and 7. Then by pushing button C the door will close, leaving the door-closing circuit open behind it at T and R. When it has closed, it bridges the rods E and F in the door-opening circuit which can then be completed by pushing button O and the door will open, leaving the door-opening circuit broken behind it at E and F, just as in closing it left the door-closing circuit broken at T and R. Thus the door, when ending its movement in one direction, automatically places the circuit in condition for future reverse movement of the door upon closing the proper switch, and when starting in one direction automatically breaks the circuit for the direction in which it has started. The push

buttons also, when establishing a circuit for one direction, automatically break the circuit for the opposite direction and leave closed the circuit which has been established.

My arrangement will be recognized as similar in certain fundamental respects to that which appears in McElroy Patent No. 1,287,717, of 1918, but it provides, in addition, for the automatic reversal of the door from its opening to its closing direction. This it does by means of the connection between the battery and rod T which is established at the points 6 and 7 by the opening push-button O and then maintained. Moreover, the addition of rod E at the opposite end provides for an interruption of the connection between E and F after the door starts to open, thereby preventing the maintaining of current on magnet O' for the entire period preceding the next pushing in of button C, which period might be of an indefinite length. By this means both the door-opening and the door-closing circuits are normally broken, one being broken at the push-button, the other at the door contacts. The manual contacts 6 and 7 are in series, in the door-closing circuit, with the contacts T and R, while in the door-opening circuit the manual contacts 4 and 5 are in multiple with the said contacts T and R at switch D.

Instead of using the short strip E, I may connect the point 5 permanently to the opening magnet O' and so arrange the operating switch that the button O will open the connection between 6 and 7, as above described, but make only a momentary closure of contacts 4 and 5. Thus in Fig. 2 the button O is disconnected from bar K and arranged like an ordinary push-button to momentarily connect points 4 and 5 when pressed. If, however, the button C is in the position shown in Fig. 1, to connect 6 and 7 the button O when pushed in will also hit the end of rod K and open 6 and 7. This gives button O a control of the door at all times, not merely when the door is closed.

What I claim as new and desire to secure by Letters Patent is:

1. The combination with a door and its operating motor of a door opening circuit for said motor and a door closing circuit for said motor, a contact mounted upon and movable with the door, and control means for the two circuits located respectively in positions to be engaged by the door carried contact at the two extremes of the door movement.
2. The combination with a door and its operating motor of a door closing circuit for said motor, two sets of circuit closing contacts in said circuit, an operator's switch for closing and maintaining the circuit to one set of contacts, and means carried by the door to close the circuit through the other set of contacts when the door is in

open position, whereby said circuit may be completed by the operator or by the door on return of the latter to its open position.

3. The combination with a door and its operating motor of a door closing circuit for said motor, two sets of contacts in series in said circuit, and means for maintaining either set closed while leaving the other set open to serve as controlling contacts for initiating closing movement of the door.

4. Electrical door control means comprising a travelling contact, a door opening circuit including control contacts positioned to be engaged by said traveling contact at one end of its limit of travel, a manual circuit closer co-operating with the travelling contact to close said circuit, a door closing circuit including control contacts positioned to be engaged by said travelling contact at the other end of its limit of travel, and a second manual circuit closer co-operating with said travelling contact to close the last mentioned circuit.

5. Electrical door closing means comprising a travelling contact, a door opening circuit normally closed by said travelling contact, a door-closing circuit, a manual switch in the last mentioned circuit capable of maintaining a normal closed position, and means co-operating with said travelling contact for automatically closing the last mentioned circuit at the end of the opening movement of the door while said manual switch is closed.

35 6. Electrical door control means comprising a door opening magnet, a manual switch therefor, a door contact controlling said magnet when the circuit is closed through said manual switch, a door closing magnet in a circuit containing contacts opened by the door contact on moving toward the open door position, and a manual switch in the door-closing circuit.

45 7. The combination with a door and its motor of a door-contact, a door-opening magnet, a door-closing magnet, a circuit for the door-opening magnet completed either by a manual switch or by the door-contact, and a circuit for the door-closing magnet completed by a manual switch or automatically by the shoe when the manual switch is closed.

50 8. The combination with a door and its motor, of a door-contact, door-opening and

door-closing magnets, manual switches in 55 circuits to both of said magnets, contacts actuated by the door-contact for energizing the door-opening magnet and contacts closed by the door at the end of its opening run for energizing the door-closing magnet. 60

9. The combination with a door and a motor therefor of two door control circuits one for controlling the opening and the other for controlling the closing of the door, a door contact controlling the first 65 mentioned circuit, and contacts for completing the door closing circuit, said contacts being positioned to be engaged by the door contact during opening movement of the door.

70 10. The combination with a door and a motor therefor of door-opening and door-closing magnets for said motor, a door-shoe and contacts operated thereby, travelling contacts on the door and a series of 75 stationary contact bars, engaged by said travelling contacts, two of said bars being bridged by said contacts and included in the circuit of the door-opening magnet, a third bar being connected to the source of 80 current supply and the fourth and fifth bars being in the circuit of the door-closing magnet and bridged by said travelling contacts.

11. The combination with a door and a 85 motor therefor, of door-opening and door-closing magnets therefor, a door-shoe and contacts operated thereby, travelling contacts operated by the door and stationary contact-bars, bridged in pairs by a travelling 90 contact, one pair in the circuit of the door-closing magnet and one in the circuit of the door-opening magnet.

12. The combination with a door and its operating motor of a circuit controlling 95 the door-opening movement, a travelling contact controlling said circuit, a switch for disabling said travelling contact when the door is closed, a spring for operating said switch, and means for releasing said 100 spring when the door is closed whereby the closing of the door precedes the closing of the switch.

Signed at New York, county of New York, State of New York, this 18th day 105 of April, 1920.

LEE P. HYNES.
